TURNTABLE FOR RAILWAY-GUNS.

1,359,977.

Specification of Letters Patent. Patented Nov. 23, 1920.

Application filed September 4, 1920. Serial No. 408,379.

To all whom it may concern:

Be it known that I, FRITZ FINCKH, residing at Essen, Germany, a citizen of the German Republic, have invented a certain new and useful Improvement in Turntables for Railway-Guns, of which the following is a specification.

This invention relates to that type of turntable for railway guns, the bridge of which has an opening for the gun barrel, when the gun is fired at an elevation and consists in the arrangement of a set of rails by means of which the opening in the bridge of the turntable can be bridged over and which rails can be thrown out of action at will.

The invention will be described with reference to the accompanying drawings in which—

Figure 1 is a side elevation of one constructional form of the turntable together with a gun in the firing position and

Fig. 2 is a section on the line 2—2 of Fig. 1 looking from the left.

Figs. 3 to 5 show views corresponding to Fig. 2 of modified constructions of the turntable.

The arrangement shown in Figs. 1 and 2 will be described first.

The bridge N of the turntable is supported at its center by a ring of balls n^1 on an underframe P. In this part of the bridge of the turntable is provided a rectangular opening n^2 (see Fig. 2), up to which rails Q (see Fig. 1) laid on the turntable, reach. When the gun is run onto the turntable, rails R extend across the opening n^2 . The rails R are carried by a sleeper grid R^1 , which is pivotally attached to the bridge of the turntable, the axes, about which the grids R^1 are swung, lying parallel with the longitudinal direction of the rails R. Struts r^2 (see Fig. 2) pivotally carried by the bridge of the turntable and which can be connected by their free ends to eyes on the grids R^1 , are provided for supporting the rails R R^1 in the position indicated by dotted lines in

Fig. 2. In this position therefore, in which the rails R form an extension of the rails Q, the line of rails R R^1 is situated, when the gun is run onto the turntable, until the axis of the trunnions lies approximately over the center of the turntable and the two bogies $H^1 H^2$ (see Fig. 1) are situated on either side of the opening n^2 . After the struts r^2 have been disconnected from the grids R^1 , the

struts r^2 and the grids R^1 are turned down into the position shown in full lines in Fig. 2. By this means the opening n^2 is laid open and so affords room for the breech i^3 of the gun barrel J, which recoils, when the gun is fired, (see the position of the breech end of the gun barrel i^3 shown in dotted lines.) A tedious dismantling of the line of rails is thus avoided and at the same time the gun can be made ready for firing very quickly.

The construction shown in Fig. 3 and the one just described differ only in that the grids R^1 for laying open the opening n^2 are not swung downward out of the horizontal position in which they are held by the struts r^2 , but are swung upward. The width of the grids R^1 is so formed in this case that they support the frame H of the carriage of the gun, which bends when the gun is fired, when they are in the position shown by full lines in Fig. 3. In this position the grids are secured by struts (not shown in the drawing).

In the construction shown in Fig. 4 the grids R^2 , which carry the rails R, are movable longitudinally in horizontal guides n^3 on the bridge N of the turntable and are pushed, (calculated from the center of the line of rails), transversely to the longitudinal direction of the rails R inward to close or outward to lay open the opening n^2 .

The construction shown in Fig. 5 has a grid R^3 , which carries both rails and extends over the whole width of the opening n^2 . The grid R^3 is movable longitudinally in vertical guides n^4 on the bridge N of the turntable, so that the line of rails R R^3 can be brought out of the path of the breech of the gun barrel i^3 by lowering it. When in the position, which it occupies, when the gun is run onto the turntable, the grid R^3 can be supported by screw gears, for example, which serve at the same time for the raising and lowering of the grid.

Claims.

1. A turntable for railway guns which comprises a bridge, said bridge being provided with an opening for the gun barrel when the gun is fired at an elevation, a line of rails and means for bringing said line of rails into position to bridge the opening.

2. A turntable for railway guns which comprises a bridge, said bridge being provided with an opening for the gun barrel

100

105

110

when the gun is fired at an elevation, grids, a line of rails supported on said grids, the grids supporting the rails adapted to be moved relatively to the bridge so that the 5 opening can be bridged over, as and for the purpose set forth.

3. A turntable for railway guns comprising a bridge, said bridge being provided with an opening for the gun barrel when the 10 gun is fired at an elevation, a pair of grids for bridging said opening hingedly mounted to the turntable on horizontal axes, rails supported by said grids, struts pivotally mounted on the grids, said grids adapted to be swung on their axes to bring the line of rails into position, said rails being adapted to be secured in said position by the struts, substantially as described.

4. A turntable of the class described, comprising a bridge, said bridge being provided with an opening for the gun barrel when the gun is fired at an elevation, grids for bridging said opening and supporting a line of

rails, said grids being so mounted on the bridge that they may be caused to support 25 the frame of a gun, substantially as described.

5. A turntable of the class described which comprises a bridge, said bridge provided with an opening, a pair of grids supporting a line of rails, said grids being movable transversely to uncover said opening.

6. A turntable of the class described which comprises a bridge, said bridge being 35 provided with an opening for a gun barrel when the gun is fired at an elevation, a grid for bridging said opening and supporting a line of rails, said grid being movable vertically, substantially as described.

The foregoing specification signed at Es-
sen, Germany, this 18th day of May, 1920.

FRITZ FINCKH.
